UNITED STATES PATENT OFFICE.

GEORGE W. DICKINSON, OF CHARLESTON, ILLINOIS.

HAME-TUG FASTENER.

SPECIFICATION forming part of Letters Patent No. 241,315, dated May 10, 1881.

Application filed November 13, 1880. (Model.)

To all whom it may concern:

Be it known that I, GEORGE W. DICKINSON, of Charleston, in the county of Coles, and in the State of Illinois, have invented certain new and useful Improvements in Hame-Tug Fasteners; and I do hereby declare that the following is a full, clear, and exact description thereof, reference being had to the accompanying drawings, and to the letters of reference marked thereon, making a part of this specification.

The nature of my invention consists in the construction and arrangement of a device for connecting and adjusting a trace to a hame-tug, as will be hereinafter more fully set forth.

In order to enable others skilled in the art to which my invention appertains to make and use the same, I will now proceed to describe its construction and operation, referring to the annexed drawings, in which—

Figure 1 represents the hame-tug and trace detached. Fig. 2 is a section of the same united. The hame-tug consists of a metal bar, A, of suitable dimensions, formed at one end with a loop, B, for the passage of a strap to connect it with the hame. At the other end the bar A forms a large loop, C, through which the end of the trace is to pass, and also smaller loops D, for the pad and back and belly bands. The metal bar A is reduced in thickness longitudinally in the center on the under side, and this reduced portion has a series of T-shaped slots, a a, made through it at equal distances apart.

The back of the bar is covered by a leather strap, E.

G represents the trace, on the end of which is securely fastened a metal plate, F, having upon its outer end a projecting plate, b, and near its inner end is a projecting T-head, d.

In attaching the trace to the hame-tug the plate b is first pushed upward through the cross part of one of the slots a until the head d can be passed through the corresponding part of the next slot, when the trace is pulled down, causing both the plate b and head d to lie behind the bar A and their shanks be in the center portions of the slots.

The trace can easily be changed in the slots to lengthen or shorten the trace, as required.

Having thus fully described my invention, what I claim as new, and desire to secure by Letters Patent, is—

The combination of the metallic hame-tug A, provided with the series of T-shaped slots a, and the trace G, provided with the plate F, having the double fastening b d attached to or forming a part thereof, thus making a double lock, substantially as herein set forth.

In testimony that I claim the foregoing I have hereunto set my hand and seal this 19th day of February, 1880.

GEORGE W. DICKINSON. [L. S.]
